Leominster, Mass., a corporation of Massachusetts

Application December 24, 1947, Serial No. 143,314

Term of patent 14 years

(Cl. D57—1)

To all whom it may concern:

Be it known that I, Bernard Ulvad, a citizen of the United States, residing at Leominster, in the county of Worcester, State of Massachusetts, have invented a new, original, and ornamental Design for a Sun-Goggle or the like, of which the following is a specification, reference being had to the accompanying drawings, forming part thereof, in which:

Fig. 1 is a top plan view of a sun-goggle or the like, showing my new design.

Fig. 2 is a front elevation thereof.

The essential features of my design reside in the parts shown in full lines.

The characteristic features of my design for a sun-goggle reside in the specific configuration of the frame, wherein the lower edges are straight and slope downwardly so as to converge at a

point below the frame, as seen in Fig. 2, in combination with the rearwardly extensions of the lenses beyond the vertical plane of the frame, as seen in Fig. 1, all as illustrated on the drawing.

I claim:

The ornamental design for a sun-goggle or the like, substantially as shown and described.

BERNARD ULVAD.
